Attorneys.*

UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed December 16, 1929. Serial No. 414,265.

My invention relates to an improvement in slicing machines and has for one purpose the provision of an improved rotary knife. Another object is the provision of improved scraping means for a rotary knife. Another object is the provision of means for preventing fragments or portions of the material being sliced from penetrating within the housing of the slicing machine. Other objects 10 will appear from time to time in the course of the specification and claims.

I illustrate my invention more or less diagrammatically in the accompanying drawings, wherein—

15 Figure 1 is an elevation;

Figure 2 is a section on the line 2—2 of Figure 1; and

Figure 3 is a section on the line 3—3 of Figure 1.

20 Like parts are indicated by like symbols throughout the specification and drawings.

Referring to the drawings, A generally indicates any suitable slicing machine base upon which may be mounted a motor not 25 shown in detail but enclosed within the housing A¹. A² indicates the shaft of said motor, A³ a drive pulley thereon and A⁴ a belt passing about said drive pulley.

B generally indicates a rotary knife mounted 30 in any suitable fashion upon the frame or base A. It may have a pulley B¹ about which passes the belt A⁴, whereby rotation of the motor serves to rotate the knife. The knife is herein shown as forwardly recessed as at B² and rearwardly recessed as at B³, the

35 rear recess being of lesser diameter than the forward recess. The forward peripheral face B⁴ may be plane, or slightly dished or concave. The rear peripheral face generally indicated as B⁵ may be generally arcuate in cross section, terminating at its inner edge in the shoulder B⁶, which bounds the recess B³. The face between the shoulder B⁶ and the cutting edge is formed with a plurality of

40 concentric annular depressions B⁷, separated by the upstanding ridges or walls B⁸. It will be observed that a portion of the frame indicated as A¹⁰ enters the rear recess B³ and approaches closely adjacent the shoulder B⁶.

45 50 Mounted upon the frame portion A¹⁰ I il-

lustrate a scraping or knife clearing or cleaning member generally indicated as C. This member C includes a portion C¹ conforming generally to or overlying the frame portion A¹⁰, as shown in Figure 2. It may be secured to it as by the screw C² passing through the slot C³ in the member C, whereby a certain measure of adjustment is provided. One edge of the member C is provided with a plurality of fingers C⁴, each one of which penetrates one of the channels or grooves B⁷.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

In particular it will be understood that I do not wish to be limited to the particular or specific arrangement or spacing or shape of grooves or channels B⁷ or of fingers C⁴, as they may be varied widely without departing from the spirit of my invention.

In employing the term "channel" as descriptive of the knife, I wish this term to be interpreted as broadly enough to cover any 55 circumferential irregularities of contour, concentric with the axis of rotation of the knife which serve to exercise the stopping or guarding function of the channels described and shown herein.

The use and operation of my invention are as follows:

In slicing machines of the type herein shown the problem of major importance is the prevention of access of material, such as 60 scraps of meat, lard, grease and the like, into the interior of the slicing machine housing or frame. The penetration of such material creates unsanitary conditions and may also shorten the life of the driving belt. In 65 the use of the device the knife is constantly rotated, at a high speed of rotation, and the work to be sliced is moved across the face and past the cutting edge of the knife, by any suitable means, the details of which are not 70

herein shown, since they do not of themselves form part of the present invention. It will be understood that as the work passes across the cutting edge of the knife slices are cut from the work and fall upon the work receiving tray A¹². Assuming that a greasy substance, such as ham or bacon is being cut, it may happen, owing to the high speed of rotation of the knife, that the material being cut is heated sufficiently to liquefy the grease or lard in it, which grease or lard may pass across the face of the knife. By employing a plurality of circumferential concentric channels I greatly reduce the tendency of this material to be wiped across the face of the knife by the slices as they are severed. The individual slots or grooves, and the raised portions of the knife between them, serve as walls or dams to prevent the access of grease, meat juices and bits of material. In order to prevent the accumulation of material in these grooves I provide the scraping means shown, including the fingers C⁴ which tend to scrape or plow out whatever material penetrates and adheres to the slots B⁷, and furthermore serve as a positive slice deflector.

Where in the description and claims I employ the terms "slot" or "groove" or "channel" I wish to mean a depression in the knife bounded at each side by a wall effectively defining one side of such groove, slot or channel.

I claim:

35. 1. In a slicing machine, a rotary knife, having a plurality of concentric channels formed in a face thereof, and a scraper, opposed to said knife, and including portions adapted to penetrate said channels.

40. 2. In a slicing machine, a rotary knife, the rear face of said knife having formed therein a plurality of concentric channels, and a scraper, opposed to the rear face of said knife, and including elements adapted to penetrate said channels.

45. 3. In a slicing machine, a rotary knife having a face channeled concentrically with the axis of rotation of said knife, and a scraper, opposed to said channeled face, and formed to penetrate the channeled portion thereof.

50. 4. In a slicing machine, a rotary knife, having a channel formed in one face thereof, adjacent the cutting edge, said channel being concentric with the axis of rotation of the knife.

55. 5. In a slicing machine, a rotary knife, the rear face of said knife being formed with a central depression, the portion of the rear face of said knife intermediate said central depression and the cutting edge being concentrically channeled.

60. 6. In a slicing machine, a rotary knife, the rear face of said knife being formed with a central depression, the portion of the rear face of said knife intermediate said central

depression and the cutting edge being formed with a plurality of concentric channels.

7. In a slicing machine, a rotary knife, the rear face of said knife being formed with a central depression, the portion of the rear face of said knife intermediate said central depression and the cutting edge being concentrically channeled, and a scraping member opposed to and penetrating said channeled portion of the knife face.

8. The structure of claim 7 characterized by the employment of a guard member penetrating said central depression, the edge of said guard member being masked by the inner edge of the peripheral portion of the knife adjacent and exterior to said central depression.

9. In a slicing machine, a rotary knife, the rear face of said knife being formed with a central depression, a guard element, penetrating said central depression, the inner edge of the peripheral portion of said knife being adapted to mask the edge of said guard element, the peripheral exposed portion of the rear face of the knife being formed with channels concentric with the axis of rotation of the knife.

10. The structure of claim 9 characterized by the employment of a scraping member opposed to and penetrating said channeled portion of the knife.

11. The structure of claim 9 characterized by the employment of a scraping member opposed to the channeled portion of the knife and mounted upon the guard element.

12. In a slicing machine, a rotary knife having a plurality of concentric channels formed in a face thereof, and a scraper, opposed to said knife, said scraper having a plurality of fingers adapted to penetrate the individual channels.

Signed at Indianapolis, county of Marion, and State of Indiana, this 19th day of November, 1929.

WILLIAM J. CAMPBELL.
